UNITED STATES PATENT OFFICE

WALTER J. PASINSKI, OF DETROIT, MICHIGAN, ASSIGNOR TO BURROUGHS ADDING MACHINE COMPANY, OF DETROIT, MICHIGAN, A CORPORATION OF MICHIGAN

BOOKKEEPING MACHINE

Application filed August 9, 1928. Serial No. 298,418.

This invention relates to a bookkeeping machine and it is directed particularly to a construction for mechanically proving the correctness of the work done by the operator.

In the use of bookkeeping machines, it is often the practice, for example, in bank work, to enter a customer's old balance by reading it off his ledger sheet and entering it on the amount keys after which the machine is given a stroke of operation which results in printing the old balance in a designated column on the ledger sheet which is generally called the "pickup" column. The machine is then tabulated to the next column where the debit items are entered, subtracted from the old balance, and printed in a "withdrawal" column. There may be one or more of these debit columns followed by a credit or "deposit" column or columns where deposits are entered and printed. After the debits have been subtracted and the credits have been added, the machine is tabulated to another column, usually called the "balance" column where a new balance is taken, printed and the machine cleared. The carriage is next tabulated to a "proof" column and this is generally done by automatically returning the carriage across the machine and stopping it in the "proof" column which is usually just ahead of the "pickup" column. It is the duty of the operator to again enter the old balance in the "proof" column by reading it from the entry on the ledger sheet from which it was first read and entering it on the amount keys of the machine. By requiring a second entry of the old balance, any mistakes that have been made in the first entry in the "pickup" column may be caught because the operator is not liable to make the same mistake twice. It is desired that the operator be notified when a mistake has been made and one of the old methods of doing this is to print a special character opposite the old balance in the proof column. If no mistake has been made, this character can be printed, but if there has been a mistake, it is impossible to print the character and the operator is thus given a signal or notified that there has been an error. The difficulty with this procedure is that the operator does

not receive the signal until after the machine has been operated and the old balance printed in the proof column, with the result that all the work must be done over again in the event that a mistake has occurred. Also, the catching of the error depends on the operator. If he fails to manipulate the special key the error will not be caught. It is highly desirable to catch the error automatically and to shorten the time required for the proving work. In so far as possible, the doing over of the work should be made unnecessary. The problem is complicated by the fact that the work in the "proof" column must be checked against that in the prior "pickup" column, and the latter may be any number of columns ahead of the "proof" column in the sequence of operations. While the carriage is in any of the intermediate positions the machine must be free to operate to perform all its normal functions. The present invention is directed to a solution of this problem.

The general object of the invention is to provide an improved automatic mechanism for proving the work done in certain columnar positions of the paper carriage of a bookkeeping machine.

A more particular object is to provide an improved mechanism for preventing effective operation of a bookkeeping machine when an entry in a "proof" column is not the same as an entry in a prior "pickup" column.

Another object is to provide a means for automatically preventing effective operation of a bookkeeping machine when the amount keys that are depressed in a certain columnar position of the paper carriage are not the same amount keys that were depressed in a prior columnar position where the same entry was to be made.

Still another object is to provide a machine which will be prevented from being operated when the second entry above described is not of the same sign as the first entry.

Other objects and advantages of the invention will appear from the specification and drawings.

The invention comprehends a machine having a mechanism which is set by the amount

keys of the keyboard when an item is entered in the machine in a given columnar position of the paper carriage. When the carriage is moved away from this column, the mechanism 5 is automatically moved to a non-operative position where it remains until a later predetermined column is reached whereupon it is automatically moved to position to cooperate with the amount keys. If the same 10 amount keys are depressed in the later column the machine is free to operate, but if the same keys are not depressed, operation of the machine is prevented. The mechanism is also controlled by the subtraction lever 15 of the machine so that the entry in the second predetermined column must be of the same sign as the first in order for the machine to be operated.

An embodiment of the invention is shown 20 in the accompanying drawings in which:

Figure 1 is a sectional side elevation of a Burroughs bookkeeping machine showing enough of the main parts to illustrate the machine to which the invention is applied, the 25 mechanism of the invention being shown in the position the parts occupy when the carriage is in the "pickup" position.

Fig. 2 is a perspective view of one of the amount keys of the keyboard together with 30 the locking device associated therewith, the parts being shown in normal position.

Figs. 3, 4, and 5 are detail sectional side elevations of a detent associated with the locking device, said detent being shown in 35 normal, partially depressed, and fully depressed position in the respective figures.

Fig. 6 is an enlarged sectional side elevation of two of the amount keys of the keyboard with the locking device associated therewith, 40 the parts being shown in normal position the same as in Fig. 2.

Fig. 7 is an enlarged sectional side elevation similar to Fig. 6 showing the parts as 45 they are positioned by the paper carriage when it is in the "pickup" column.

Fig. 8 is a view similar to Fig. 6 showing the position of the parts when one of the keys is depressed after the parts have been positioned as in Fig. 7.

Fig. 9 is a view similar to Fig. 6 showing the position of the parts after the locking 50 mechanism which has been set as in Fig. 8 has been withdrawn and the keys returned to normal.

Fig. 10 is a view similar to Fig. 6 showing the position of the parts when the carriage is in its "proof" column, and before any keys 55 have been depressed.

Fig. 11 is a view similar to Fig. 6 showing 60 the position of the parts in the "proof" column when an attempt is made to operate the machine with the wrong key depressed.

Fig. 12 is a side elevation illustrating the 65 mechanism for restoring the locking device to normal prior to restoring the amount keys.

Fig. 13 is a view similar to Fig. 12 showing the operation of the restoring mechanism in the "proof" column.

Fig. 14 is a side elevation of the locking 70 connections for the motor starting mechanism showing the parts in normal position.

Fig. 15 is a detailed side elevation of a portion of the locking connections for the motor starting mechanism showing the parts in the position they occupy when the carriage 75 is in "pickup" position and the motor starting bar is normal.

Fig. 16 is a view similar to Fig. 15 showing the position of parts when the motor bar is depressed.

Fig. 17 is also a view similar to Fig. 15, but showing the position of the parts when the carriage is in its "proof" column and the motor starting bar is normal.

Fig. 18 is a side elevation of the locking 80 connections for the motor starting mechanism showing the position of the parts when the carriage is in its "proof" column and the mechanism is locked against starting the machine.

Fig. 19 is a detail plan view illustrating 85 how the locking mechanism is controlled by the control lever when said lever is in "add" position.

Fig. 20 is a view similar to Fig. 19 showing 90 how the mechanism is controlled by the shift lever when it is in "subtract" position.

Fig. 21 is a side elevation of the restoring 95 mechanism illustrating how it is operated by the general error key, the parts being shown in normal position.

Fig. 22 is a detailed side elevation of the lower rear portion of the mechanism illustrated in Fig. 21, showing the position of the parts when the paper carriage is in the 100 "pickup" column and the error key is undepressed.

Fig. 23 is a view similar to Fig. 21 showing the position of the parts in the "proof" column with the error key undepressed.

Fig. 24 is a rear elevation of the carriage controls for the locking mechanism.

Fig. 25 is a rear elevation of the upper part 105 of the machine showing particularly the locking mechanism parts that are combined with the usual Burroughs construction.

Fig. 26 is a plan view of an example of work that may be performed on the machine.

The invention is illustrated as applied to a Burroughs bookkeeping machine the general features of which are sufficiently well known to make a detailed description unnecessary. Briefly, the machine includes a plurality of actuator racks 610 carried by arms 611 whose rear ends support printing types 618 that may be driven into engagement with a platen P carried by the traveling paper carriage C. The carriage is automatically tabulated back and forth across the machine to different columnar positions by 115 120 125 130

mechanism of the type disclosed in Rinsche Patent No. 1,580,584 to which reference is made for details. The machine has one or more counters 916 for cooperation with the 5 actuator racks 610 and it is provided with a subtract lever 10, by means of which it may be conditioned for addition or subtraction. Items are entered in the machine on a plurality of amount keys 291 which, when depressed, 10 rock bell crank detents 217 to pull wire stops 270 into position to stop the actuator racks in differential positions. Depression of a key in a particular bank moves a slide 214 for that bank rearwardly which releases 15 a latch 415 to release the rack bar 610. The slide 214 is held rearwardly by a latch 228 thus holding the amount key depressed until near the end of the operation of the machine when all the latches 228 are released 20 by a bail 202. The latch 228 and its slide for each bank may also be released individually by means of an individual column release key R or all of them may be released simultaneously by depression of a general error key E 25 shown in Fig. 21.

Mechanical proving mechanism

The work is proved by preventing operation of the machine in the "proof" column 30 unless the entries made in said column are the same as those made in the "pickup" column. If no entries were made in the "pickup" column, none should be made in the "proof" column, the proving mechanism operating 35 under these conditions also, as will be described later. In order to lock the machine against operation in the "proof" column, mechanism is provided which is set by depression of the amount keys in the entering of an 40 item in the "pickup" column, which mechanism allows free operation of the machine until the carriage reaches the "proof" column whereupon it acts to prevent operation of machine unless the same amount keys are 45 depressed in the "proof" column as were depressed in the "pickup" column. A locking mechanism is associated with each bank of keys, but, inasmuch as the mechanism for each bank is the same, the description will be 50 confined to one bank, it being understood that the constructions for the other banks is the same.

Referring to Fig. 2 which shows one of the 55 amount keys 291, it will be observed that the stem of this key is provided with an extra slot 20, which, in certain positions of the parts, receives a stud 21 carried by a detent 22. This detent is pivoted at 23 on a slide 24 that is mounted at the side of the bank of 60 keys, being guided and limited in its movement by one or more studs 25 such as illustrated in Fig. 2. The detent 22 is held in either of its two positions, which will be later described, by means of a spring 26 one end of 65 which is connected to the stud 21 and the

other end to a stud 27 carried by the slide 24. As shown in Figs. 3, 4 and 5, the detent is 70 slideable on its pivot 23 to an extent determined by the slot 28. The forward edge of the detent 22 is cam shaped and two notches 29 and 30 are provided which cooperate with the stud 27 to position it. The normal position of the detent is illustrated in Fig. 3 where the line of action A—B of the spring 26 is illustrated as above the pivot 23. When 75 the rear, or right hand end of the detent as viewed in Fig. 3 is moved downwardly the detent moves through the position of Fig. 4, where the line of action A—B of the spring 26 passes through the pivot 23, until it reaches the position of Fig. 5 where the line of spring 80 action A—B is below the pivot. From this it will be clear that the spring 26 acts to hold the detent in either of its two-center positions after it has been moved across center. 85

Each detent 22 is provided with a tail 31 that is normally positioned above a slot 32 in the keyboard plate 33. When the detent is in its normal position, illustrated in Figs. 2 and 3, the tail piece is above the plane of the 90 plate 33, but when the detent is moved downwardly to the Fig. 5 position, the tail 31 projects into the slot 32. If, while the detent is in the Fig. 5 position, the slide 24 is moved forwardly far enough, that is, to the left in 95 Fig. 5, the detent will be carried sufficiently to the left, if the slide is moved far enough, to cause the left hand edge of the slot 32 to engage the tail piece 31 and cam the detent back to normal position. The detents in each 100 bank may thus be restored by movements of the sliding bars 24 sufficient to cause any detents that are out of normal position to be cammed back to normal.

When the paper carriage is in its columnar 105 positions for performing ordinary operations, the slide 24 with its detents 22 is in the position illustrated in Fig. 6, where the amount keys 291 are free to operate without having any effect on the detents and the 110 machine functions in a normal manner.

When, however, the carriage is moved to the "pickup" column it acts automatically to move all the sides 24 rearwardly to position the studs 21 on the detents 22 in the slots 20 115 of the stems of the amount keys. The connections for accomplishing this are illustrated most clearly in Figs. 1 and 24. The paper carriage C is provided with a large roller 40, cooperating with one arm 41 of a pivoted 120 yoke-shaped member 42 whose other arm 43 has a bifurcated-end engaging one end of a pivoted lever 44. The other end of lever 44 is connected to a vertical link 45 which is urged upward to normal position against a 125 stud 46 by spring 47. The upper end of link 45 is connected by a pin and slot connection 48—49 to one arm of a bell crank lever 50 pivoted loosely on a shaft 51. The other arm of the bell crank lever is connected to a 130

bail shaft 52 to which the rear ends of all of the slides 24 are connected. A spring 53 normally maintains the pin 48 in the bottom of the slot 49 in link 45. The roller 40 is so positioned and is of such size that, when the carriage reaches the "pickup" column, the roller depresses the arm 41 to pull down the link 45 which, through the medium of spring 53 acts to rock the bell crank 50 counter-clockwise to thereby move the bail 52 rearwardly a distance sufficient to move all of the studs 21 into the slots 20 in the key stems. The positions of the amount keys and the detents 22 under this condition are illustrated in Fig. 7.

Accordingly, when one of the amount keys is depressed when the machine is in the "pickup" column, its detent 22 is rocked downwardly, as illustrated for the right hand key in Fig. 8. Both the key and the detent are temporarily latched in position, the key by the usual slide 214 heretofore mentioned and the detent by the spring 26 and notch 29. When an item is entered in the "pickup" column a certain number of amount keys will be depressed and hence a certain number of detents corresponding to said keys will be depressed.

After an item has been entered on the keys in the "pickup" column, the machine is given a forward and a return stroke of operation and during the latter part of the return stroke the carriage automatically tabulates to the next columnar position. As the carriage moves to the next column, roller 40 moves away from the arm 41, which is thereupon released, and the spring 47 draws upwardly on the link 45 which rocks the bell crank lever 50 clockwise and moves the bail 52 forward to the Fig. 9 position to move all the slides 24 forward to remove the studs 21 from the slots 20. This occurs prior to the release of the amount keys and hence, when the studs 21 are moved out of the slots 20, the detents that have been positioned by depression of amount keys in entering the item in the "pickup" column remain depressed, the position of the parts being illustrated in Fig. 9. As the stroke of the machine is finished the amount keys are released by the usual releasing bail 202 and they move back to normal undepressed positions for the entry of items in other columns, but their return to normal does not return the detents 22 to normal because all of them have been moved so that their studs 21 are out of slots 20.

It is important that the detents be moved out of active position before the keys are released in order to prevent the restoration of the keys from restoring the detents to normal, and, while ordinarily the detents are so moved because their controlling mechanism is released by the carriage prior to the release of the amount keys, nevertheless provision is made for positively insuring that

the parts will be operated in the desired sequence. The amount keys are released by the usual oscillating bell crank 622-630 (Figs. 12 and 13) mounted on shaft 600 and carrying the pass-by pawl 623 urged to position by spring 618 and adapted to contact a roller 232 on one end of an arm 219 whose other end carries the release bail 202 that contacts all of the latches 228 for the release of the key latching slides 214. Pivoted on the shaft 51, which carries the bell crank lever 50, is an arm 54 connected at its upper end to the bail 52 and having a roller 55 on its lower end positioned in the path of the pass-by pawl 623. When the bell crank lever 50 is rocked counter-clockwise by the carriage in the "pickup" column, as heretofore described, the arm 54 is moved through bail 52 to position roller 55 in the path of the pass-by pawl 623 as shown in Fig. 12 so that, as the oscillating arm 630 moves counter-clockwise during the latter part of the return stroke of the machine, the pawl 623 first contacts the roller 55 and, if the slides 24 have not been previously moved forward by the action of spring 47 as previously explained, they are positively moved forward prior to the release of the amount keys, the latter being caused by the subsequent contact of the pass-by pawl 623 with the roller 232. In this manner forward movement of all of the detents is insured prior to release of the amount keys so that all of the studs 21 will be out of the slots 20 before the amount keys are raised to normal position. This forward movement of the slides 24 is not enough to cause the detents 22 to be caused back to normal if they have been depressed but leaves them in the position of Fig. 9.

From this it will be observed that the item entered on the amount keys in the "pickup" column is set up in the proof mechanism and that said mechanism is then automatically moved out of active position where it will not be disturbed again until wanted for proof purposes.

When the carriage moves to columns after the "pickup" column, the machine operates in a normal manner and items may be entered on the keyboard and the machine operated without affecting the detents 22 because all these detents are in their forward position, illustrated in Figs. 6 and 9, where the studs 21 are out of the paths of the slots 20 in the key stems. The slides 24 are held in this position by the spring 47 which holds the link 45 upward against the stud 46 and the bail 52, with its slides 24 forward. It is only when the carriage occupies a position where the control roller 40 moves the slides 24 rearward that the detents 22 are positioned for operation by the amount keys.

After the carriage has gone through the necessary operations in intermediate columns

it is tabulated to the "proof" column where another roller 56 (Fig. 24) similar to the roller 40 but slightly smaller, moves the slides 24 rearward automatically to the position illustrated in Fig. 10, where the studs 21 are just short of the forward edges of the key-stems. The parts are stopped in this position so as to leave the amount keys free for manipulation without frictional contact with the studs 21. When the carriage is in the "proof" column, it is the duty of the operator to again enter the old balance on the amount keys and, if this is entered correctly, the same keys should be depressed as were depressed when the amount was entered in the "pickup" column. If this is done, the slots 20 in the depressed keys will be opposite the studs 21 of the detents 22 that were depressed in the "pickup" column and which still remain depressed and all the slides 24 will be free to move rearward which they must do in order for the motor starting mechanism to operate as will be later described. If an error has been made by the depression of a key that was not depressed in the "pickup" column, the slot 20 in the stem of the wrongly depressed key will move away from the path of the stud 21 of the detent for that key as illustrated in Fig. 11. Also, if one of the keys that previously had been depressed is not depressed, the slot 20 in the stem of that key will not be moved down where it will be in the path of stud 21 of the depressed detent 22 for that key as is also illustrated in connection with the right hand key in Fig. 10. In other words, unless exactly the same keys are depressed in the "proof" column as were depressed in the "pickup" column, one of the slides 24 will be blocked against rearward movement because of the engagement of the stud 21 on one of its detents 22 with the edge of one of the key-stems. Inasmuch as all of the slides 24 are connected to the cross-shaft or bail 52 rearward movement of this bail is prevented and this prevents starting of the motor as will now be described.

It will be plain that if no keys were depressed in the "pickup" column the locking action will take place if any keys are depressed in the "proof" column. In such event none of the detents 22 would have been depressed in the "pickup" column and hence all the keys would have to remain undepressed in the "proof" column. Otherwise, one of the slots 20 in the depressed key would be out of line with its undepressed detent and rearward movement of its slide 24 would be prevented.

Locking connections for power drive

The motor is caused to give the machine a stroke of operation by depression of the usual starting bar 60 (Fig. 14) which rocks the lever 61 counter-clockwise and, through the spring 62, moves the link 63 upwardly. Upward movement of this link starts the driv-

ing mechanism in the well known manner explained, for example, in Vincent Patent No. 866,750. The lever 61 carries a stud 64 which is positioned to contact a cam surface 65 on a lever 66 pivoted at 67. The upper end of lever 66 is connected to one end of a spring 68 whose other end is connected to a hooked projection 69 on a link 70 having an abutment projection 71 for engaging the square stud 72 on the vertical link 63. The forward end of the link 70 is bifurcated and it straddles a stud 73 on the lever 66. The link 70 also has a cam surface 74 engaging a stud 75 on an arm 76 projecting rearwardly from the lever 66. The spring 68 provides a yielding connection between the lever 66 and the link 70, the lever 66 being also urged clockwise by a spring 77. In normal operation, depression of the bar 60 rocks lever 61 counter-clockwise which tensions spring 62 and raises the link 63 to start operation of the machine. When lever 61 is rocked, it cams lever 66 counter-clockwise which pulls the link 70 to the left in Fig. 14 to cause abutment 71 to pass far enough to the left across the path of stud 72 to permit free upward movement of link 63.

The rear end of the link 70 is provided with a T-shaped slot 80 having a vertical portion 81. A stud 82 operates in the T-shaped slot, said stud being on the lower end of an arm 83 pivoted loosely on shaft 51 and being connected to the bail 52 to which the slides 24 are connected.

The normal position of the parts is illustrated in Fig. 14 where the stud 82 is in the horizontal part of the slot 80 and slightly to the rear of the vertical portion 81. When the motor bar is depressed under these conditions, the stud 64 contacts the surface 65 and cams the lever 66 counter-clockwise which pulls the link 70 forward, the link being free to move because the stud 82 moves freely in the slot 80.

When the carriage positions the bail 52 so as to move all the slides 24 rearwardly as it does in the "pickup" column, the stud 82 is positioned in the forward part of the slot 80 as illustrated in Fig. 15. Here again the link 70 is free to move forward when the motor bar is depressed, the position of the link with the motor bar depressed being shown in Fig. 16.

When, however, the carriage positions the bail 52 in its intermediate position, as it does when the carriage is in the "proof" column, the stud 82 is immediately above the vertical portion 81 of the slot 80 as illustrated in Fig. 17. Accordingly, when the motor bar is depressed, the first action caused by the contact of stud 64 with surface 65 of arm 66 which acts through spring 68 is to swing the link 70 counter-clockwise which moves the vertical portion 81 of the slot 80 over the stud 82 thereby locking the link 70 to the arm 83. When

the link 70 and arm 83 are connected together, further movement of the link 70 forward will tend to rock the arm 83 clockwise and, if the same amount keys have been depressed in the "proof" column as were depressed in the "pickup" column, the motor is started as usual. If, however, any of the wrong keys have been depressed or the right ones have not been depressed, some of the slides 24 are blocked in the manner heretofore explained and the bail 52 with its arm 83 cannot move and the link 70, likewise, cannot move forward. Depression of the motor bar 60 rocks the lever 66 counter-clockwise but, the link 70 being blocked, the only result is the stretching of spring 68. The abutment 71 on link 70 is not moved far enough forward to clear the path of the square stud 72 on the link 63 and hence the link 63 cannot rise to a position to start the motor.

In order to prevent misoperation by accidental engagement of the stud 82 in the vertical portion 81 of the slot 80 when the link 70 is moving back and forth, a V-shaped lock 84 is provided which is positioned to cooperate with the hook-shaped end 85 of the arm 86 integral with the rear end of the link 70. When the link 70 is moved forward under normal conditions from the position of Fig. 14 to that of Fig. 16, the hook-shaped end 85 moves under the V-shaped member 84 and locks the link 70 against vertical movement. The same thing occurs when the link 70 is moved forward from the Fig. 15 position. When the link 70 is moved upwardly as in Fig. 18 such movement occurs prior to any forward movement of the link and the hooked end 85 moves out of the vicinity of the V-shaped member 84. It is only when the parts are in the Fig. 17 position that the link 70 can swing upward to affect a locking action.

Control by subtraction lever

It is important, if the item entered in the machine when the carriage is in "pickup" position is entered with the subtraction lever in addition position, that the subtraction lever be in the same position when the item is entered with the carriage in the "proof" position. The item entered in the "pickup" position might be either positive or negative and the proof in the "proof" column should also prove the positive or negative character of the item entered. Accordingly, a control is provided which depends upon the position of the subtraction lever, the same being illustrated in Figs. 19 and 20.

A slide 90 is provided on the keyboard which is similar to and which operates in the same manner as the slides 24 heretofore described, it being also connected to the bail 52 to which said slides are connected. Mounted on the end of this slide is a detent 91 having a double-notched end 92 cooperating with a stud 93 and provided with a spring 94 for

holding it in position, one end of the spring being connected to the stud 93 on the slide 90 and the other to a stud 95 on the pivoted detent 91. The stud 95 is adapted to move into a notch 96 in a pivoted arm 97 having a cam slot 98 in which the subtraction lever 10 operates. The operation of this control is, in general, the same as that previously described for the amount keys, to wit:

Assume that the lever 10 is in the addition position illustrated in Fig. 19 and that the detent 91 is in the position there shown on the slide 90, but the slide is in its forward position such that the stud 95 is not in the slot 96. When the carriage tabulates to its "pickup" position the slide 90 is moved rearwardly together with the slides 24 and the stud 95 moves into the slot 96. If the subtraction lever remains in its addition position the parts remain in the relative positions shown. When the paper carriage moves away from the "pickup" position the slide 90 is moved forward so as to remove the stud 95 from the slot 96 and the subtraction lever may be freely moved without affecting the detent 91. When the carriage reaches the "proof" column, the slide 90 is again moved rearwardly but not so far, the distance being simply enough to bring the stud 95 to a position slightly short of the edge of the arm 97. If, in the "proof" column, the subtraction lever remains in addition position the slide 90 is free to move farther rearwardly with the slides 24 in the starting of the motor and there will not be any blocking of the starting mechanism, but if the subtraction lever should be moved to subtraction position in the "proof" column, the lower edge of the arm 97 will move in front of the stud 95 and full rearward movement of the slide 90 cannot take place until the subtraction lever is moved back to addition position to locate the slot 96 in front of the stud 95. This blocks operation of the machine in the same manner as when one of the slides 24 is blocked.

If, when the carriage is in the "pickup" column, and after the slide 90 has been moved rearward by the carriage so as to position the stud 95 in the slot 96, the subtraction lever is moved to subtraction position, the parts will be moved to the position illustrated in Fig. 20. The detent 91 is moved to its second position where it will be held by the spring 94. As the carriage tabulates, the slide 90 again moves forward and the stud 95 moves out of the slot 96. When the carriage reaches the "proof" column, the slide 90 is returned rearwardly a short distance sufficient to position the stud 95 just short of the lower edge of the arm 97. If the subtraction lever remains in subtraction position the slot 96 remains in front of the stud 95 and slide 90 is free to move rearwardly to permit operation of the motor starting mechanism, but if, under

these conditions, the subtraction lever should be moved to addition position, the edge of the lever or arm 97 will move in front of the stud 95 and rearward movement of the slide 5 90 will be blocked so as to prevent starting of the motor.

In this manner operation of the machine is prevented unless the subtraction lever occupies the same position in the "proof" column 10 as it occupied in the "pickup" column.

The detent 91 normally occupies the addition position of Fig. 19. When it is moved to the subtraction position of Fig. 20 it is later restored to addition or normal position 15 at the time all the parts are restored. This is done by means of a pin 99 which is positioned so that when the slide 90 is moved forward to release the parts, as will be later described, the detent 91 strikes the pin 99 and 20 is moved to the Fig. 19 position.

Releasing means

The mechanism may be released in several ways, depending upon the error involved and 25 the desires of the operator.

Assume that the machine has reached the "proof" column and that a wrong key has been depressed or that one of the keys that should have been depressed has not been depressed. Depression of the motor bar will 30 not operate the machine and the operator immediately knows that an error has been made somewhere and he is notified of this fact before the error is printed. His first check is to 35 see whether there has been an error in making the entry in the "proof" column. To do this, aside from observing the keys depressed, he must release the amount keys and enter the item (old balance) again.

40 He can easily release the amount keys by depressing the usual column release keys R (Fig. 1) for the banks of keys in which amount keys have been depressed. This simply restores the amount keys and does not 45 disturb the slides 24 and the associated locking mechanism. He does not want to move the slides 24 to release the detents 22 because, if he did so, the set up of the "pickup" 50 column item (the first entry of the old balance) would be released from the proving mechanism, a result that is not yet desired.

Instead of using the column release keys for releasing the keys the operator may use the general error key E which is arranged 55 so that, by a partial depression, the amount keys will be released without releasing the detents 22, whereas by full depression both the amount keys and the detents will be released. This mechanism is illustrated in 60 Figs. 21, 22 and 23.

The error key E is carried by a bell crank lever 100 having a link 101 pivoted to its end. The outer end of this link has a slot 102 in it 65 which operates over a stud 103 on the arm 219 carrying the bail 202 which releases the

latches 228 for releasing the amount keys. The link 101 also has a downwardly extending branch 104 having a stud 105 adapted to engage the end of a pass-by pawl 106 pivoted at 107 to an arm 108 pivoted on the shaft 51 and connected to the bail 52 that controls the slides 24 and 90. The pawl 106 has a nose 109 positioned to engage a stud 110 on a stationary member 111 supported on shaft 51 and provided with an arm 112 having a bifurcated end straddling the shaft 121 on which the arm 219 is pivoted. The member 111 is thus held against rocking movement. The pawl 106 is normally maintained in engagement with the stud 110 by a spring 113. 70 In the no roller positions of the carriage where the bail 52 is not moved but occupies the Fig. 21 position, the pawl 106 is maintained out of and below the path of the stud 105 as illustrated. When the carriage is 75 moved to the "pickup" column, the bail 52 is rocked rearward, as viewed in Fig. 21, by means of the large roller 40 on the carriage acting through the link 45. This moves the arm 108 with its pawl 106 to the position of 80 Fig. 22 where the stud 110 cams the pawl to the Fig. 22 position where it is above the path of stud 105. When the carriage is moved to any of its intermediate no roller 85 positions prior to reaching the proof column, the parts occupy the Fig. 21 position above 90 described. When the carriage moves to the "proof" column, the smaller roller 56 acting through link 45 rocks the bail 52 to a position which moves arm 108 to the position of Fig. 23 where the pawl 106 is in the path of 95 the stud 105. If the error key E is fully 100 depressed when the parts are in this position, the stud 105 will engage the end of pawl 106 and rock the arm 108 counter-clockwise. 105 This rocks the bail 52 forward which moves the slides 24 (and 90) forward far enough to cause the detents 22 to be restored to normal by the camming action of the keyboard plate 33 heretofore explained.

110 From the above it will be clear that, when the carriage is in any of its positions other than the "proof" position, the error key E may be depressed to release the amount keys in the usual manner without disturbing the proof mechanism but, when the carriage is in its "proof" position, full depression of the error key will restore the proof mechanism to normal as well as release the amount keys.

115 If, with the carriage in its "proof" position, it is desired to release only the amount keys by means of the error key rather than by the column release keys, the error key is only partially depressed. The slot 102 in the link 101 which is moved by depression 120 of the error key, is positioned so that the end of the slot engages the stud 103 prior to the engagement of the pawl 106 by the stud 105. If the error key is only partially depressed, 125 the end of slot 102 engages stud 103 to move 130

the arm 219 to move bail 202 to release the latches 228 to thereby release the amount keys, but the stud 105 does not move far enough to engage the pawl 106 so that the locking mechanism is not released, the position of the parts being shown in dotted lines in Fig. 23.

Returning now to the proving operations, let it be assumed that the machine did not operate in the "proof" column and that the operator has restored the amount keys either by depressing the individual column release keys or by partially depressing the error key. He then carefully enters the item (old balance) again and, if it is entered correctly and if the error was in the "proof" column, the machine can be operated. He can thus quickly correct an error in the "proof" column without having had it printed on the ledger sheet and without having to start the entire posting operation over again.

It may happen that the error is in the position of the subtraction lever in the "proof" column. This would prevent operation of the machine the same as if an error had been made on the amount keys. This error would ordinarily be checked at the same time that the second entry in the "proof" column was made because the operator, in making the second entry, would be careful to enter the old balance as of the correct sign as well as the correct amount.

If, after making the second entry in the "proof" column to check the correctness of the work in the "proof" column as to sign and amount, the machine will not operate, the operator knows that the error has occurred elsewhere, to-wit, in the first entry in the "pickup" column. The condition is that, although the correct amount keys are depressed and although the subtraction lever is in correct position in this "proof" column, the set-up in the proof mechanism does not correspond because this set-up was incorrectly put into the proof mechanism by an incorrect entry of the old balance when it was first entered in the "pickup" column. This error can be checked by observing the printed entry that was made in the "pickup" column on the ledger sheet. In the event of such an error it is necessary to do the work over again. The operator moves the carriage back to the "pickup" column and after running a pencil or pen line through the incorrect posting, starts over again. It should be noted that, although the work must be done over again when the error is made in the "pickup" column, it is impossible to proceed in the "proof" column under said condition. The machine is automatically locked against operation and the operator notified of the error. The notification does not depend upon the operator manipulating some special key to test for an error, an operation that might easily be overlooked. Instead, the notification is automatic and it is definite, in that,

no operation of the machine results when the motor bar is depressed. The notification always occurs before printing in the "proof" column which saves a tremendous amount of time if the error happens to be in the "proof" column because, in such event, the machine is unlocked when the correct keys are depressed and when the subtraction lever is put in the correct position, whereupon the operations may proceed without requiring that any of the work be done over again such as would be necessary if the notification did not take place until after an erroneous entry had been made in the "proof" column.

It will be readily understood that if an error should be discovered in the depression of the keys or the position of the subtraction lever in the "pickup" column, and before the machine had been operated in said column; the parts can be readily restored to normal by depression of the general error key. This restores the amount keys and the subtraction lever to normal in the usual manner and it also restores the detents 22 because, at that time, the detents are positioned so that their studs 21 are in the slots 20 of the amount keys and restoration of the keys restores the detents. The same thing applies to the detent 91 which is in the slot 96 of the subtraction lever.

Restoring mechanism

When operations have been completed in the "proof" column it is necessary to restore all the parts to normal and this is done automatically.

Referring to Fig. 12, the amount keys 291 are released in the usual manner by rocking of the restoring bail 202 through the pass-by pawl 623 and arm 630, which releases the latches 228 and permits the amount key slides 214 to move forward. The pass-by pawl 623 also contacts the roller 55 on arm 54, but, even though this happens, it does not release the detents 22 (and 91) because the parts are proportioned so that the pawl 623 never moves the arm 54 far enough to move the slides 24 (and 90) sufficiently to cam the detents 22 to normal. Accordingly, some other provision must be made for releasing the detents and this takes the form of an arm 120 shown in Fig. 13. This arm is fixed to the shaft 121 which rocks with the arm 219. Its lower end is positioned to contact a stud 122 on a downward projection 123 on the link 70. When the link 70 is swung upward to the position of Fig. 13, as it is when the motor bar is depressed in the "proof" column, as heretofore described, the link is connected to the arm 83. Near the end of the return stroke of operation of the machine, the shaft 121 is rocked counter-clockwise by means of the shaft 600, arm 630, pawl 623 and roller 232 on the arm fixed to the shaft 121. The arm 120 is positioned

on shaft 121 so that it contacts the stud 122 to move the link 70 and arm 73 far enough to move the bail 52 and slides 24 and 90 to their farthest forward position. This causes the 5 detents 22 on slides 24 to engage the keyboard plate 33 which cams them back to normal. The detent 91 on slide 90 engages the stud 99 which cams it back to normal. The operation of the parts is, of course, timed 10 so that the above action takes place before the link 70 is disconnected from the arm 83 at the end of the operation of the machine. Inasmuch as the link 70 is not connected to the arm 83 in any position of the carriage 15 other than the "proof" position, it will be evident that the above automatic restoring action takes place only in the "proof" column.

Sample of work

20 A sample of the work that may be performed is illustrated in Fig. 26 which shows a sample entry of items on a simple bank ledger. 25 In this sample, a depositor has an old balance of \$100.00. When the operator picks up the ledger sheet he enters the old balance of \$100.00 in the "pickup" column and the machine then automatically tabulates to the "withdrawal" column where an item of \$75.00 is entered indicating that the customer has 30 withdrawn \$75.00. The machine then tabulates to the "deposit" column where a \$200.00 credit item is entered indicating that the customer has deposited \$200.00 to his account. The machine then tabulates to the "balance" column where a new balance is 35 taken and printed, which, in this case, shows as a \$225.00 credit or deposit balance. An asterisk is printed opposite it indicating that 40 it is a deposit balance. The carriage then automatically returns across the machine to the "proof" column and here the operator must again look at the old balance of \$100.00 and re-enter it, that is, he must re-enter the 45 balance by reading the entry that he first read from the ledger sheet. If the old balance is entered correctly, the starting bar may be operated and the machine tabulates over to the "pickup" column for the next 50 operation. However, if a mistake has been made in the entry of the old balance, depression of the starting bar will not result in an operation and there will be no printing of the old balance in the "proof" column. Instead, 55 the operator will be immediately notified that an error has been made and he is notified prior to the printing operation. He can then depress the column release keys or partially 60 depress the error key and re-enter the old balance in the "proof" column, being careful to have it correct both as to amount and sign. If the machine then operates on depression 65 of the motor bar he knows that the error has been corrected, but, if it does not operate, he knows that an error has been made in the

original entry in the "pickup" column so that it is necessary to do the work over again. He can condition the machine for this purpose by fully depressing the error key which releases the amount keys together with the 70 slides 24 and 90 and their detents so that the item can be again entered in the "pickup" column and the operations repeated.

Among the advantages of the construction 75 it will be readily appreciated that one of the most important ones is that the existence of an error is indicated before printing occurs in the "proof" column which permits a correction if the error has been made in that column and a proceeding with operations 80 without having to return and do all the work over again. Also, the operator cannot go ahead and make other entries and get the account mixed up so that an entire rechecking 85 is necessary.

It is to be understood that the construction shown is for purposes of illustration only and that variations may be made in it without departure from the spirit and scope of the invention as defined by the appended 90 claims.

I claim:

1. In combination, in a calculating machine having depressible amount keys, a proving mechanism set by entry of an item in 95 said machine, means for automatically conditioning said proving mechanism to permit subsequent operation of the machine independent of said proving mechanism, and means controlled by said proving mechanism 100 and said amount keys and conditioned automatically prior to a subsequent operation of the machine in which said item is to be again entered for preventing said subsequent operation of the machine unless the same amount keys are depressed in entering said item as 105 were depressed when it was first entered.

2. In combination, in a calculating machine having depressible amount keys, a proving mechanism associated with said keys and set by depression of the keys upon the 110 entry of an item thereon, devices controllable by said proving mechanism for preventing operation of the machine, and means for automatically conditioning said proving mechanism for control by said amount keys 115 and for control of operation of the machine prior to a predetermined subsequent operation of the machine in which said item is to be again entered to thereby prevent operation 120 of the machine unless the same amount keys are depressed in the second entry of said item as were depressed in the first entry thereof.

3. In combination, in a calculating machine 125 having depressible amount keys, a proving mechanism set by depression of said keys in entering an item thereon, means for automatically moving said proving mechanism to inactive position to permit subsequent opera- 130

tions of said keys independent of said proving mechanism, said means acting automatically to move said proving mechanism to active position for a predetermined subsequent operation of the machine where said item is to be again entered on said keys, and means controlled by said proving mechanism for preventing said subsequent operation of the machine unless the same amount keys are 10 depressed in the second entry of said item as were depressed in the first entry thereof.

4. In combination, in a calculating machine having depressible amount keys, a proving mechanism set by the entry of an item in said machine, means for automatically conditioning said proving mechanism to permit subsequent operations of the machine independent of said mechanism, and means automatically placed under the control of said amount keys and said proving mechanism after a predetermined number of operations of said machine for preventing operation of the machine until the same amount keys only are depressed as were depressed when said item was first entered thereon.

5. In combination, in a calculating machine having depressible amount keys and means for operating the machine, a proving mechanism set by depression of the amount keys in entering an item thereon, means for automatically moving said proving mechanism to inactive position after it has been set to permit subsequent operations of the machine independent of said proving mechanism, and connections conditioned automatically to operatively connect said proving mechanism with said operating means for a predetermined subsequent operation of the machine in which the same item is to be again entered on the amount keys, said amount keys acting through said proving mechanism to prevent said predetermined subsequent operation of the machine unless the same amount keys are 45 depressed upon the second entry of the item as were depressed upon the first entry thereof.

6. In combination, in a calculating machine having depressible amount keys and a traveling paper carriage, a proving mechanism set by the entry of an item in said machine, means controlled by the carriage for automatically conditioning said proving mechanism to permit subsequent operations of the machine independent of said proving mechanism, and means conditioned by said carriage in a subsequent predetermined columnar position thereof and controlled by said amount keys and said proving mechanism for preventing operation of the machine until the same amount keys only are depressed in entering said item as were depressed when it was first entered.

7. In combination, in a calculating machine having depressible amount keys and a traveling paper carriage, a proving mechanism

associated with said keys and set by depression of the latter upon the entry of an item in a predetermined columnar position of the carriage, devices controllable by said proving mechanism for preventing operation of the machine, and means controlled by the carriage for automatically rendering said proving mechanism inactive to permit subsequent operations of the machine independently of said mechanism, said means also acting automatically to condition said proving mechanism for control by said amount keys in a subsequent predetermined columnar position of the carriage in which said item is to be again entered to thereby prevent operation of the machine unless the same amount keys are depressed as were depressed when said item was first entered.

8. In combination, in a calculating machine having depressible amount keys and a traveling paper carriage, a proving mechanism set by depression of said amount keys in entering an item thereon in a predetermined columnar position of the carriage, means controlled by said carriage for automatically moving said proving mechanism to inactive position after it has been set to thereby permit subsequent operations of the machine independent of the proving mechanism, said means acting automatically to move said proving mechanism to active position in a subsequent predetermined columnar position of the carriage where said item is to be again entered on said keys, and means controlled by said proving mechanism for preventing said subsequent operation of the machine when the same amount keys are not depressed in the entry of said item in said subsequent columnar position of the carriage as were depressed in the first entry.

9. In combination, in a motor driven calculating machine having depressible amount keys and a controlling mechanism for causing the motor to operate the machine, a proving mechanism set by the entry of an item in said machine, means for automatically conditioning said proving mechanism to permit subsequent operations of the machine independent of said proving mechanism, and means automatically conditioned prior to a subsequent operation of the machine in which said item is to be again entered therein and controlled by said amount keys and said proving mechanism for disabling said controlling means unless the same amount keys are depressed in entering said item as were depressed in the first entry thereof.

10. In combination, in a motor driven calculating machine having depressible amount keys, a traveling paper carriage, and a controlling mechanism for causing the motor to operate the machine; a proving mechanism associated with the machine and set thereby upon the entry of an item in a pre-

- determined columnar position of the carriage, and means controlled by the carriage in a subsequent predetermined columnar position thereof in which said item is to be again entered for conditioning said proving mechanism for control by said amount keys to disable the controlling mechanism from operating the machine until the same amount keys only are depressed in the second entry 5 of said item as were depressed in the first entry thereof.
11. In combination, in a motor driven calculating machine having depressible amount keys and a controlling mechanism for causing the motor to operate the machine, a proving mechanism operatively associated with said amount keys and set by depression of them in entering an item thereon, means for automatically moving said proving mechanism to inactive position after it has been set to thereby permit subsequent operations of said keys independent of the proving mechanism, said means acting to automatically move said proving mechanism to active 15 position for a predetermined subsequent operation of the machine in which the item first entered is to be again entered on the keys, and means controlled by said proving mechanism for disabling said controlling mechanism when the same amount keys are not depressed in the second entry of said item as were depressed in the first entry thereof.
12. In combination, in a motor driven calculating machine having depressible amount keys, controlling mechanism for causing the motor to operate the machine, and a traveling paper carriage; a proving mechanism set by depression of the amount keys in entering an item thereon in a predetermined 20 columnar position of the carriage, means controlled by said carriage for automatically moving said proving mechanism to inactive position after it has been set to thereby permit subsequent operations of the machine independent of the proving mechanism, and connections controlled by said carriage for automatically connecting said proving mechanism with said controlling mechanism in a subsequent predetermined columnar position of the carriage where said item is to be again entered on the amount keys, said amount keys acting through said proving mechanism to disable said controlling mechanism to thereby prevent operation of the machine unless the same amount keys are depressed upon the second entry of said item as were depressed upon the first entry thereof.
13. In combination, in a motor driven calculating machine having amount keys, a controlling mechanism for causing the motor to operate the machine, and a traveling paper carriage; a proving mechanism associated 25 with said amount keys and set by depression of said keys in entering an item thereon in a predetermined columnar position of the paper carriage, means operated by said paper carriage for automatically moving said proving mechanism out of operative relation with said amount keys when the paper carriage moves away from said predetermined columnar position, said carriage operated means acting to move said proving mechanism into operative relation with said amount keys in a subsequent predetermined columnar position of the carriage, and normally disconnected connections conditioned by said carriage in said subsequent predetermined columnar position for connecting said proving mechanism with said controlling mechanism so that manipulation of said controlling mechanism tends to move said proving mechanism, said amount keys acting to block said proving mechanism to disable said controlling mechanism when the same amount keys are not depressed in said subsequent columnar position of the carriage as were depressed in the first columnar position thereof.
14. In combination, in a calculating machine having banks of depressible amount keys and means for operating the machine, a slide for each bank carrying detents adapted to be set by depression of the amount keys of its bank, means for automatically moving said slides to move said detents out of operative relation with said amount keys after said detents have been set by depression of said keys in entering an item thereon, and means for automatically connecting said slides and operating means prior to a predetermined subsequent operation of the machine where the same item is to be entered on said keys, said keys acting to prevent said slides from moving sufficiently to permit said operating means to effect said subsequent operation of the machine unless the same amount keys are depressed in the second entry of said item as were depressed in the first entry thereof.
15. In combination, in a calculating machine having banks of depressible amount keys, operating means for the machine, and a traveling paper carriage; a slide for each bank carrying detents adapted to be set by depression of the amount keys of its bank, means controlled by the carriage for automatically moving said slides to move said detents out of operative relation with the amount keys after said detents have been set by depression of the keys in entering an item thereon, and means controlled by the carriage for automatically connecting said slides to said operating means in a predetermined subsequent columnar position of the carriage, said keys acting to prevent said slides from moving to thereby prevent said operating means from effecting said subsequent operation of the machine unless the same amount keys are depressed in said subsequent columnar position

of the carriage as were depressed in entering said item in the first columnar position of the carriage.

16. In combination, in a motor driven calculating machine having banks of depressible amount keys, a traveling paper carriage, and a controlling mechanism for causing the motor to operate the machine; a slide for each bank of keys carrying detents adapted to be set by depression of the keys of its bank in entering an item thereon, means controlled by the paper carriage for automatically moving said slides to move said detents out of operative relation with the keys after said detents have been set in entering an item, and connections conditioned by the paper carriage in a subsequent columnar position thereof to connect the slides to the controlling mechanism to thereby make it necessary to move the slides in operating the controlling mechanism to operate the machine, said amount keys preventing movement of said slides except when the same keys are depressed as were depressed when said item was first entered in the machine.

17. In combination, in a motor driven calculating machine provided with banks of depressible amount keys having key stems, a traveling paper carriage, and a controlling mechanism for causing the motor to operate the machine; a slide for each bank of keys carrying detents adapted to be received in slots in the stems of the keys of its bank and to be set by depression of said keys in entering an item on them in a predetermined columnar position of the carriage, means controlled by the paper carriage for automatically moving said slides to move said detents out of operative relation with the keys after said detents have been set, said carriage controlled means acting to return said slides to return said detents adjacent the key stems in a subsequent predetermined columnar position of the carriage where said item is to be again entered on the keys, and connections conditioned by said carriage in said subsequent columnar position thereof for connecting the slides to the controlling mechanism to thereby make it necessary to move said slides in operating the controlling mechanism to operate the machine, said amount keys preventing movement of said slides except when the same keys are depressed to position the slots in the key stems in position to receive said detents.

18. In combination, in a calculating machine having a conditioning means for conditioning the machine for addition or subtraction, a proving mechanism associated with said conditioning means for control thereby during the entry of an item in the machine, and means for automatically placing said proving mechanism in control of operation of the machine for a predetermined subsequent operation where said item is to be again en-

tered, to thereby prevent said operation of the machine unless the conditioning means is in the same condition for the second entry of said item as it was for the first.

19. In combination, in a calculating machine having a conditioning means for conditioning the machine for addition or subtraction, a proving mechanism associated with said conditioning means for control thereby during the entry of an item in the machine, means for automatically rendering said proving mechanism inactive after an item has been entered to permit subsequent operations of said conditioning means independent of the proving mechanism, said means having provisions for automatically rendering said proving mechanism active prior to a predetermined subsequent operation of the machine where the same item is to be entered a second time, and means controlled by said proving mechanism for preventing said subsequent operation of the machine when said conditioning means is not in the same condition at the time of the second entry of said item as it was at the time of the first entry thereof.

20. In combination, in a calculating machine having a traveling paper carriage and a conditioning means for conditioning the machine for addition or subtraction; a proving mechanism associated with said conditioning means for control thereby during the entry of an item in the machine, means controlled by said paper carriage for moving said proving mechanism out of operative relation with said conditioning means to permit subsequent operations of the machine independent of said conditioning means, said carriage controlled means having provisions for automatically moving said proving mechanism into operative relation with said conditioning means in a predetermined subsequent columnar position of the carriage where the same item is to be entered a second time, and means controlled by said proving mechanism for preventing operation of the machine in said subsequent columnar position of the carriage when the conditioning means is not in the same condition at the time of the second entry of said item as it was at the time of the first entry thereof.

21. In combination, in a calculating machine having an operating means, a conditioning means for conditioning the machine for addition or subtraction, and a traveling paper carriage; a proving mechanism associated with said conditioning means for control thereby during the entry of an item in the machine in a predetermined columnar position of the carriage, means controlled by said carriage for moving the proving mechanism out of operative relation with the conditioning means when the carriage moves away from said predetermined co-

- lumnar position, and mechanism controlled by said carriage for automatically connecting said proving mechanism to said operating means in a subsequent predetermined 5 columnar position of the carriage where the same item is to be again entered in the machine, said conditioning means acting through said proving mechanism to prevent operation of the machine by said operating 10 means in said subsequent position of the carriage when said conditioning means is not in the same position for the second entry of said item as it was for the first entry thereof.
- 15 22. In combination, in a motor-driven calculating machine having a controlling mechanism for causing the motor to operate the machine, a traveling paper carriage, and a conditioning means for conditioning the 20 machine for addition or subtraction; a proving mechanism associated with said conditioning means for control thereby during the entry of an item in the machine in a predetermined columnar position of the carriage, said conditioning means being automatically left free for subsequent operations, and connections controlled by said carriage for automatically placing said controlling mechanism under control of said 25 proving mechanism in a predetermined subsequent position of the carriage where said item is to be again entered to thereby disable said controlling mechanism unless said conditioning means is in the same condition 30 for the second entry of said item as it was for the first.
23. In combination, in a calculating machine having an operating means, depressible amount keys, a traveling paper carriage, 40 and a subtraction lever and connections for conditioning the machine for addition or subtraction; a slide associated with said lever carrying a detent adapted to be set by movement of said lever from addition to subtraction position in a predetermined columnar position of the carriage, means controlled by the carriage for automatically moving said slide to move said detent out of operative relation with said subtraction 45 lever when the carriage moves away from said predetermined columnar position, means for connecting said slide to said operating means in a predetermined subsequent columnar position of the carriage where said 50 item is to be entered a second time, said subtraction lever acting to prevent said slide from moving to thereby prevent said subsequent operation of the machine when said 55 subtraction lever is not in the same position when said item is entered in said machine the second time as it was when said item was first entered.
- 60 24. In combination, in a calculating machine having amount keys, an error key with 65 connections for restoring depressed amount keys, and a traveling paper carriage; a proving mechanism associated with said amount keys and set by depression of said keys when an item is entered thereon in a predetermined columnar position of the carriage, means controlled by said carriage for automatically rendering said proving mechanism inactive when said carriage moves away from said columnar position, said carriage 70 controlled means acting to render said proving mechanism active in a subsequent predetermined columnar position of the carriage where said item is to be again entered on said keys, connections controlled by said proving mechanism for preventing operation of the machine in said subsequent columnar position of the carriage unless the same amount keys are depressed as were depressed when the item was first entered, and connections conditioned by said carriage in said subsequent predetermined columnar position for enabling the error key to restore said proving mechanism to normal.
- 75 25. A calculating machine having depressible amount keys, means for operating the machine, a proving mechanism set under control of said amount keys when they are depressed by the entry of an item thereon, and means controlled by said proving mechanism prior to a subsequent operation of the machine in which said item is to be again entered for compelling depression of all of the same amount keys as were depressed during the first entry of said item in order 80 to operate the machine.
- 85 26. A calculating machine having depressible amount keys, means for operating the machine, a traveling paper carriage, a proving mechanism set by depression of said amount keys in the entry of an item thereon in a given columnar position of the carriage, means for rendering said proving mechanism inactive after it has been set, means for automatically rendering said proving mechanism active in a predetermined subsequent columnar position of said carriage, and means controlled by said proving mechanism in said subsequent columnar position of said carriage for compelling depression of all of the same amount keys as were depressed in the entry of said item in said first columnar position in order to operate 90 the machine.
- 95 27. In combination in a calculating machine having depressible amount keys, a proving mechanism set by the entry of an item in said machine, said mechanism being positioned to permit subsequent operations of the machine independently of said proving mechanism, means acting to establish cooperative relationship between said proving mechanism and said amount keys prior to a predetermined subsequent operation of the machine in 100 105 110 115 120 125 130

which said item is to be again entered in the machine, and means controlled by said amount keys and said proving mechanism acting to prevent said predetermined subsequent operation of the machine unless the same amount keys are depressed as were depressed upon the first entry of said item.

5 In testimony whereof, I have subscribed my name.

WALTER J. PASINSKI.
